UNITED STATES PATENT OFFICE

CHARLES C. SHIPMAN, OF BREA, CALIFORNIA

PITMAN COUNTERBALANCE

Application filed September 30, 1930. Serial No. 485,420.

The object of my invention is to provide a new and improved means for counterbalancing the weight of a string of the rods used in pumping deep wells.

5 It is well known that the weight of the pump rods must be counterbalanced to prevent excessive power consumption and undue strains on the pumping equipment. It is customary to provide counterbalances, which 10 heretofore have been attached either to the band wheel by which the pumping crank is actuated or to the crank itself or to the crank end of the walking beam.

I have discovered that it is highly advantageous to attach the counterbalance weight to the pitman or preferably to a downward extension thereof, the advantages being that the weight is placed much lower and in a position where it is readily accessible; that 20 the weight is taken off revolving parts and reciprocating strains are thereby avoided, and finally the wear on the wrist pin bearing is greatly reduced and it is made much easier to lubricate.

25 In the accompanying drawings Fig. 1 is a side elevation of the customary Samson post and walking beam of an oil pumping rig connected operatively with a steel or wood pitman bearing my improved counterbalance.

30 Fig. 2 is a side elevation, in section, of my counterbalance and the lower end of the pitman to which it is attached.

In the drawings, 10 is the Samson post, 11 the walking beam, 12 the pitman and 13 35 the crank, these being parts of the usual pumping rig.

I extend the pitman downwardly below the wrist pin bearing as indicated at 14 and fix in this extension a pin 15. From this pin I 40 suspend a suitable weight 16 which may be in the form of a heavy plate, flat on the side which comes next to the pitman. To this plate may be attached any desired number of additional weights, in the form of rectangular plates 17, by means of the bolts 18.

I prefer to suspend this weight from a pin, as shown in the drawings, in such manner that it will maintain an upright position, but it is within the scope of my invention to attach the weight rigidly to the lower extremity 50 of the pitman.

I claim as my invention:

1. In a well pumping rig having a pitman: a counterweight for the pumping rods having the form of a plate and being swingingly attached to the extreme lower end of said pitman at a point near the upper edge of said plate and substantially on the vertical axis of said plate. 55

2. An apparatus according to claim 1 in which the plate bears transverse openings for the reception of bolts, whereby additional plates may be attached to the first. 60

3. An apparatus according to claim 1 in which the plate is suspended in a position on the central axis of the pitman from a wrist pin passing through the latter, said weight being able to swing freely on said wrist pin. 65

In witness that I claim the foregoing I have hereunto subscribed my name this 25th day of Sept., 1930.

CHARLES C. SHIPMAN.

UNITED STATES PATENT OFFICE

WILLIAM E. SHORE, OF WEST NEW BRIGHTON, NEW YORK, ASSIGNOR TO SHORE CORPORATION, OF DOVER, DELAWARE, A CORPORATION OF DELAWARE

ROTARY COMPRESSOR

Application filed April 9, 1928. Serial No. 268,489.

The principal objects of this invention are, to improve the construction of a compressor such as described in my pending application No. 160,194 filed January 10th 1927, whereby the strain and wear on the working parts will be reduced to the minimum, and whereby the efficiency of the machine will be considerably enhanced.

The principal features of the invention consist in the novel construction of the rotary vane member and the means for supporting same whereby an impeller vane operating in a radial slot in the rotor member is supported by an extension thereof having bearing surfaces engaging bearing supports arranged at either side to maintain the axis of the vane in parallel relation with the rotor axis and to prevent axial movement of the impeller.

A further feature of importance in the present invention consists in the novel construction of the compressor casing, whereby the discharge from one cylinder is staged within the pump casing to supply the adjacent cylinder, thereby subjecting the medium under compression to substantially instantaneous changes of pressure and temperature with the minimum of transfer of heat to the compressor mechanism.

A still further feature of importance consists in the novel arrangement of a bye-pass between the initial intake passage and the final discharge passage to enable the recycling of the medium under treatment, to effect a raising of the operating temperature.

In the drawings, Figure 1 is a vertical midsectional and part elevational view of a compound compressor unit constructed in accordance with the present invention.

Figure 2 is a horizontal sectional view of the unit illustrated in Figure 1.

Figure 3 is an end elevational view looking in the direction of arrow, Figure 1.

Figure 4 is a sectional elevational view taken through a first stage cylinder on the line 4—4 Figure 2.

Figure 5 is a sectional elevational view through the second stage cylinder taken on the line 5—5 of Figure 2.

Figure 6 is a perspective view of the dou-

ble impeller vane showing the bearing supports for the vane in sectional perspective.

Figure 7 is a central sectional view through the dual impeller vane.

In my previous application I have shown 55 a pair of pump cylinders eccentrically arranged and each having therein an eccentric rotor and an impeller vane operating in said cylinders and engaging said rotors and formed of a rigid unit comprising two right 60 angularly placed vanes but it has been found in practice that much higher speeds of operation can be obtained by reason of the improved construction of the impeller vane and 65 its bearing supports.

It has also been ascertained that the two cylinder casings may be advantageously constructed from the one pattern, thus facilitating the handling of the mechanical construction of the device.

In the present construction each cylinder casing 1 is formed with a cylinder chamber 2 which is of a peculiar formation to accommodate the peculiar movement of the impeller vane.

The transverse axis A—A extending through the division wall 3 is arranged in alignment with the axis of the rotor 4, and the impeller 5 when in engagement with the division wall extends across the diameter of 80 the cylinder and engages the opposite side thereof.

The axis of the rotor is offset laterally from the centre of the cylinder towards the division wall 3 and the walls of the cylinder 85 casing on either side of the transverse axis curve outwardly from the cylindrical to accommodate the movement of the impeller vane which by the rotation of the rotor moves off the axis of the cylinder.

Each of the casings 1 are formed with the cylindrical recessed portion 6 eccentric to the cylinder chamber 2 into which the outer end of each of the rotors 4 extend.

A sleeve extension 7 projects from the cylindrical recessed portion 6 and is concentric therewith and in each of said sleeve extensions are arranged the roller and ball bearing races 8 and 9 respectively.

The rotors are provided with the shaft ex- 100

- tensions 10 and 11 respectively supported in the ball and roller bearings carried by said races and are thus very effectively journalled to revolve true at a high rate of speed.
- 5 The open side of each of the cylinder casings 1 is formed with a counter-bored recess 13 and a ring 14 formed with a flange 15 on its perimeter is fitted into said recesses and thus centralizes the two casings.
- 10 A flat ring 16 abuts the outer edge of the flange of the ring 14 and fits in the opposite counter-bore. These two rings are constructed of a hard bearing material and are ground very accurately with their inward faces parallel.
- 15 Each of the rotors 4 is formed with a transverse slot 17 and these are set in right angular relation to each other to receive the right angularly disposed sections of the impeller vane.
- 20 The impeller vane is formed with the two flat sections 18 and 19 arranged in right angular relation to each other and crossing each other centrally of their length.
- 25 Each of the vane sections is formed with a centrally arranged shank portion 20 which flares outwardly from their flat faces to meet the right angularly disposed circular flange or disc 21.
- 30 The disc 21 is spaced from the inner edge of each vane section a distance equal to the thickness of the rings 14 and 16 and the thickness of the disc 21 is equal to the depth of the flange 15 of the ring 14.
- 35 The flat surfaces of the disc 21 are very accurately ground to form a sliding bearing against the inward faces of the rings 14 and 15 and as the rings 14 and 15 are rigidly supported between the abutting end faces of the cylindrical casings 1, bearing supports are provided which form a very rigid bearing for the impeller vane.
- 40 The rings 14 and 16 have to be divided into half sections in order that they may be placed around the disc 21 of the impeller vane and it is preferable to score these discs on their outward sides and then crack them to break them into half sections so that they will when fitted together form a fluid tight joint without unnecessary machine work.
- 45 This construction of the impeller vane, together with the arrangement of the bearing surfaces therefor in the form of rings described, is extremely important. The rings are centered in the cylindrical casings and virtually form a part thereof and constitute the inward end walls of the cylinder chambers, as the ends of the rotors abut the outward faces of said rings in sliding contact.
- 50 The end faces of the rotors abutting the rings 14 and 16 and the engaging faces of the disc 21 and the rings 14 and 16 are preferably liquid sealed with a suitable lubricant which will be maintained in contact with the engaging surfaces by centrifugal action.
- 55 Other means of lubricating the contacting surfaces may of course be adopted or materials may be used which will dispense with lubrication.
- 60 Each of the cylinder casings is provided with intake and outlet recesses 22 and 23 respectively arranged on opposite sides of the division wall 3 and these recesses open into the cylinder chambers 2.
- 65 One of the cylinder casings has an outlet passage 24 leading to the recess 23 which is below the rotor and the outlet chamber or recess 23 connects through a transverse passage 25 to the inlet chamber of the adjacent cylinder casing as the compression chambers of the two cylinder casings are in diametrical offset relation as is seen particularly on reference to Figures 3, 4 and 5.
- 70 The intake of one cylinder chamber is arranged at the bottom, while the intake of the other cylinder chamber is arranged at the top, consequently the discharge of the second cylinder is arranged in juxtaposition to the intake of the first cylinder and a passage 26 connects the chambers.
- 75 A valve seat 27 is arranged in one of the casings in the passage 26 and the valve 28 is arranged in the other cylinder casing adapted to close against the valve seat to thus close the interconnecting passage but when such valve is open it will be seen that the compressed fluid discharged from the second stage casing may be circulated back into the primary intake of the first cylinder casing.
- 80 It will be understood from this description that the arrangement of the pair of ground guiding rings engaging the rigid disc section of the rotor vane will hold the vane perfectly true in relation to its axis, preventing any play or weaving, while allowing the vanes to move in their natural orbit between the two centres of the adjacent rotors. This orbit is created by the sliding of the vanes in the slots at right angles to each other with the rotors rotating in unison on different axes.
- 85 The arrangement of the central disc maintains the vanes in perfect alignment with the slots at all times and prevents the vanes from tilting in the rotor slots through the necessary working play allowed in order to allow perfect freedom of movement of the vanes in the rotors.
- 90 A very peculiar movement is effected by the vanes in following the mean axes of rotation of the rotors which causes the supporting disc in the centre thereof to revolve between the bearing rings with an eccentric sliding movement. This bearing maintains the vanes of the impeller in a constantly true position in relation to the respective rotors.
- 95 Another important feature of this centralized disc bearing is that it prevents endwise movement and consequently end thrust of the ends of the vanes against the ends of the cylinder casings and also prevents end wear.

of the vanes against the rings, the thrust all being taken on a true flat disc surface.

It will also be seen that the centrifugal action maintains a thorough lubrication between the thrust bearing surfaces formed by the rings engaging the vane disc and a liquid seal is formed when a fluid lubricant is used to prevent the passage of fluid pressure from one cylinder to the other and thus forms an intercalated compensating bearing.

Though in the specification and claims I have termed my device a compressor, it will be understood that its use does not necessarily involve the building up of any particular degree of pressure. The pressure at the outlet end of the device obviously depends upon the conditions and may be greater than or equal to, or less than atmospheric pressure. The word compressor as herein used is to be so understood.

What I claim as my invention is:—

1. In a rotary compressor, the combination with a pair of cylinder casings eccentrically arranged in relation one to the other and rotors eccentrically mounted in each of said casings and each having a transverse slot therein and an impeller formed of a pair of right angularly arranged vanes engaging the transverse slots of said rotors, of means operating in a fixed plane interposed between said right angularly arranged vanes in right angular relation to the rotor axes and adapted by contact with fixed portions of the compressor to support said vanes in true parallel relation to the axes of said rotors.

2. In a rotary compressor, the combination with a pair of cylinder casings eccentrically arranged in relation one to the other and rotors eccentrically mounted in each of said casings and each having a transverse slot therein and an impeller formed of a pair of right angularly arranged vanes engaging the transverse slots of said rotors, of an annular member inserted between the cylinder casings and abutting the adjacent ends of the rotors and closing the chambers between the rotors and the cylinder walls, and a rigid annular extension on said impeller engaging said annular member in sliding rotative contact.

3. In a rotary compressor, the combination with a pair of cylinder casings eccentrically arranged in relation one to the other and rotors eccentrically mounted in each of said casings and each having a transverse slot therein and an impeller formed of a pair of right angularly arranged vanes engaging the transverse slots of said rotors, of a flat disc rigidly united with and forming a unitary part of the impeller having its flat faces spaced from the inner edges of the vanes thereof, and a pair of spaced ring members rigidly secured between the abutting ends of the cylinder casings and extending between the inner ends of the impeller vanes and the

flat faces of said disc and forming a guide for the impeller.

4. A rotary compressor, comprising a pair of cylinder casings eccentrically arranged in relation one to the other and having concentrically arranged counterbores in their open abutting ends, a flanged bearing ring seated in one of said counterbores and extending into the other counterbore to position the cylinders, a bearing ring arranged in the opposing counterbore and having its adjacent face spaced from the face of the aforesaid bearing ring, a disc rotatively and slidably arranged between the spaced faces of said bearing rings having raised projections from either side each terminating in an impeller vane extending into the adjacent cylinders and arranged in right angular relation to each other, and transversely slotted rotors journalled eccentrically in offset relation in said cylinders.

5. A rotary compressor, comprising a pair of cylinder casings each having a cylinder chamber arranged in diametrical offset relation the one to the other, rotors arranged one in each cylinder chamber and in diametric offset relation the one to the other each engaging an opposite side of the cylinder wall, inlet and discharge passages in each of said cylinder casings communicating with the cylinder chamber, the discharge from one cylinder chamber being connected with the inlet to the adjacent cylinder chamber, an impeller formed of a pair of rigidly united right angularly arranged vanes extending transversely through the axes of said rotors, and means interposed between the opposing ends of said cylinder casings and the opposing end faces of said rotors forming a seal therebetween separating the respective cylinder chambers of said casings.

6. A rotary compressor, comprising a pair of cylinder casings each having a cylinder chamber arranged in diametrical offset relation the one to the other, rotors arranged one in each cylinder chamber and in diametric offset relation the one to the other each engaging an opposite side of the cylinder wall, inlet and discharge passages in each of said cylinder casings communicating with the cylinder chamber, the discharge from one cylinder chamber having a passage connected with the inlet to the adjacent cylinder chamber, and the inlet of the first cylinder chamber being connected with the discharge from the second cylinder chamber, a valve controlling the passage between the discharge of the second chamber and the inlet of the first chamber, a disc rotatably mounted between said cylinder chambers and having rigid impeller vanes extending therefrom in right angular relation to each other and engaging said rotors, and means for supporting said disc in a plane in right angular relation to the axes of the cylinders.
